UNITED STATES PATENT OFFICE.

BERNHARD SOKOLOW, OF NEW YORK, N. Y.

CORSET-FASTENING.

1,047,582.

Specification of Letters Patent. Patented Dec. 17, 1912.

Application filed May 4, 1912. Serial No. 695,241.

To all whom it may concern:

Be it known that I, BERNHARD SOKOLOW, a citizen of the United States of America, residing at the borough of Brooklyn, county of Kings, city and State of New York, have invented certain new and useful Improvements in Corset-Fastenings, of which the following is a full, clear, and exact description.

This invention relates to an improvement in clasps or fastenings for corsets, and has for an object to provide a jaw member adapted to grasp the buttons on the button-member of a corset fastening.

My improved device consists of a number of corset steels, one of which is stationary or fixed to one member of a corset, the other being movable and adapted to operate locks, suitable means being provided to keep said locks normally closed.

Other features of improvement will hereinafter appear.

I will now proceed to describe my invention in detail, the novel features of which I will point out in the appended claim, reference being had to the accompanying drawing, forming part hereof, wherein:

Figure 1 is a face view of my improved device; Fig. 2 is an enlarged cross-sectional view, the section being taken on a line *a—a* in Fig. 1; Fig. 3 is an enlarged fragmentary view of the lower end of the device; and Fig. 4 is an enlarged detail view of the link.

My invention consists of a steel 1 which comprises a support and which is fastened to one member or half of the corset. Adjacent the support 1 is located a movable bar 2, which lies in a recess 2^a in the support 1. To the support 1 I secure or rivet jaws 3 adapted to receive the buttons on the other element of the corset securing device, which is not shown for the reason that it is a well known element in this class of devices. To the support 1 I also pivotally secure locks 4 by means of rivets 4^a, one end of each lock being pivotally secured to the bar 2 as at 5. The outer end of each lock 4 is provided with a nose 5^a, which overlaps the jaw 3 and acts to confine the button in said jaw.

To operate the bar 2, I provide a lever 6 which is connected to the lower end of the bar 2, by a link 7, the link being pivotally

secured to the bar 2 and lever 6, as at 8 and 9. The lever 6 is pivotally secured to the support 1 as at 6^a. One end of the link 7 is provided with a finger 10 which acts as a stop in connection with a nib 11 on the lever 6, which is forced against the said finger by a spring 13, the free end 14 of which bears against a pin 15 on the lever 6. The lever 6 is actuated by means of an attached tab 12. The spring 13 keeps the locks 4 normally closed. The stop 10 and nib 11 together act to limit the movement of the lever 6 in the direction of the arrow. When the tab 12 is pulled downwardly, the lever 6 will be rotated toward the right, thereby opening the locks 4, at which time the buttons on the button-member can be withdrawn, for disengaging the members of the corset, or inserted for clasping the said members. The jaws 3 are provided with rearwardly directed projections 16, which act as a guide for the bar 2 and upon which the bar rests.

It will be seen, by referring to Fig. 2 that the upper and lower surfaces of the bar 2 and support 1 are flush or in alinement, whereby a flat structure is provided which will not cause a ridge in the corset.

Having now described my invention, what I claim and desire to secure by Letters Patent is:

A corset clasp member, comprising a support, locks pivotally secured intermediate their ends to said support, a movable bar pivotally secured to one end of said locks, jaws carried by said support, a nose carried by each of said locks overlapping said jaws, a lever pivotally secured to said support, a link connecting said lever and said movable bar, a projecting finger carried by said link, a nib carried by said lever adapted to contact with said finger when the pivotal points of which connect said link with said bar and said link with said lever come in substantial alinement with the pivotal point of said lever and said support, and a spring tending to keep said finger and said nib in contact.

Signed at New York city, N. Y., this 1st day of May, 1912.

BERNHARD SOKOLOW.
